DEPOLYALKYLATION PROCESS FOR PRODUCING PARA-t-BUTYL TOLUENE

Robert J. Lee, La Marque, Joe T. Kelly, Galveston, and Harmon M. Knight, La Marque, Tex., assignors to The American Oil Company, Texas City, Tex., a corporation of Texas

No Drawing. Application October 14, 1955
Serial No. 540,611

3 Claims. (Cl. 260—671)

This invention relates to the preparation of t-butylated aromatic hydrocarbons by reaction of a polyisobutylene and a hereinafter defined aromatic hydrocarbon.

It is normal to produce t-butyl aromatic hydrocarbons such as t-butyltoluene by the direct alkylation of toluene or other aromatic hydrocarbon with isobutylene. The production of an essentially pure t-butyltoluene requires the use of very high purity isobutylene, which olefin is an expensive item of commerce.

It has been known that diisobutylene can be used with certain acid catalysts to produce t-butylated aromatic hydrocarbons such as t-butyltoluene. However, with the catalyst taught in the art, this depolyalkylation process for the production of t-butylated aromatic hydrocarbons is inefficient because of low yields, high catalyst consumption and numerous side reactions. Such a depolyalkylation process is of considerable commercial interest because polyisobutylenes, such as diisobutylene and triisobutylene are very readily obtained in high purity at relatively cheap cost.

An object of the invention is a process for the preparation of t-butylated aromatic hydrocarbons such as t-butyltoluene. Another object is a process for utilizing polyisobutylene as a source of "iso-C₄" groups for the preparation of t-butylated aromatic hydrocarbons. Still another object is a depolyalkylation process utilizing polyisobutylene for the preparation of substantially pure para-t-butyltoluene in very high yield. Yet another object is a depolyalkylation process utilizing alkylatable benzene hydrocarbons and a polyisobutylene, which process utilizes a relatively cheap catalyst having a long catalyst life. Other objects will become apparent in the course of the detailed description.

Briefly, the process involves a depolyalkylation reaction of one or a mixture of the aromatic hydrocarbons, benzene, alkylbenzene, dialkylbenzene and trialkylbenzene, wherein the alkyl group contains from 1 to 4 carbon atoms, these aromatic hydrocarbons being capable of accepting a t-butyl substituent, with either diisobutylene, triisobutylene, or tetraisobutylene to obtain a t-butylated aromatic hydrocarbon product. The aromatic hydrocarbon may contain more than one type of alkyl group; the preferred alkyl groups are methyl and ethyl. The reaction is carried out in the presence of a BF₃-hydrate type catalyst which contains from about 66 to 80 weight percent of BF₃. The reaction is carried out at a temperature between about 0° C. and 120° C.

The aromatic hydrocarbon charged to the process must be alkylatable by at least one "iso-C₄" group. The iso-C₄ group is defined herein as one which will produce a t-butyl substituent. Suitable aromatic hydrocarbons are benzene, methyl or ethylbenzene, dimethyl or diethylbenzene, or ethylmethylbenzene, 1,2,3-trimethyl or triethylbenzene or a mixture of these alkyl groups. The invention is particularly suitable for the preparation of mono-t-butylated aromatic hydrocarbons such as mono-t-butylbenzene and t-butyltoluene. By proper adjustment of the catalyst, time, and temperature, it is possible to obtain a t-butylated

2

monoalkylbenzene which is substantially entirely para oriented, for example, para-t-butyltoluene.

The olefin charged to the process is a polyisobutylene containing from 2 to 4 iso-C₄ groups. The iso-C₄ group 5 may be considered as the equivalent of an isobutylene molecule for the purposes of alkylation. Thus diisobutylene contains 2 iso-C₄ groups and tetraisobutylene contains 4 iso-C₄ groups. Because it is very readily available in extremely high purity and appears to depolymerize 10 somewhat more readily, it is preferred to utilize diisobutylene.

It is desired to produce an alkylate which is principally the mono-t-butylated aromatic hydrocarbon. In order to attain this object, the mole ratio of alkylatable hydrocarbon charged and the polyisobutylene is adjusted so that at least about 1 mole of aromatic hydrocarbon is present for each iso-C₄ group present. To illustrate: When charging toluene and diisobutylene, at least about 15 2 moles of toluene are present for each mole of diisobutylene. When charging triisobutylene, at least about 20 3 moles of toluene would be present per mole of triisobutylene. The presence of more aromatic hydrocarbon is helpful in maximizing the yield of the mono-t-butylated product. In general, as much as 3 moles of aromatic hydrocarbon per mole of iso-C₄ groups or even more may be present in the reaction zone. It is preferred to operate with about 1.5 moles of aromatic hydrocarbon per mole of iso-C₄ group. To illustrate: When utilizing toluene 25 and diisobutylene, the preferred mole ratio of toluene to diisobutylene is about 3.

The catalyst utilized in the depolyalkylation process of the invention is a BF₃-hydrate type. The catalyst may consist essentially of BF₃ and water in the desired ratios.

Or, the catalyst may contain hydrocarbonaceous materials 35 dissolved therein from previous use as a catalyst in the depolyalkylation reaction. The amount of BF₃ present in the catalyst is between about 66 and 80 weight percent. When utilizing essentially only BF₃ and water, the mole ratio of BF₃ to water corresponds to about that 40 of the monohydrate, i.e., a mole ratio of 1. Operation with the lower concentrations of BF₃ tends to produce lower yields of alkylate based on aromatic hydrocarbon charged. Operation with the higher concentrations of 45 BF₃ produces excellent yields of alkylate, but the t-butylated alkylbenzenes tend to be high in meta oriented materials. When it is desired to produce substantially only the para oriented t-butylalkylbenzene, it is preferred to utilize a catalyst containing from about 69 to 72 weight percent of BF₃.

50 At least a catalytically effective amount of the catalyst must be present in the reaction zone. Some depolyalkylation reaction will occur with even very small amounts of catalyst which might be described as that amount which exceeds solubility of the catalyst in the hydrocarbons. In 55 general, the volume ratio of total hydrocarbon charge to the reaction zone to the catalyst will be from about 1 to 15. It is to be understood that smaller ratios and larger ratios may be used. It is preferred to operate with a volume ratio from about 5 to 9. The term "total hydrocarbons charged" is intended to include the aromatic hydrocarbons plus the polyisobutylene charged to the reaction zone.

In order to obtain appreciable amounts of the t-butyl aromatic hydrocarbon product, it is necessary to operate 65 at a temperature of at least about 0° C. At lower temperatures, direct alkylation plays an important part and octyl aromatics are produced when utilizing diisobutylene. At temperatures above about 120° C., cracking reactions come into play and it is more difficult to obtain high purity t-butyl aromatic hydrocarbons in good yields. At the very low temperatures, time does play a part in the production of high yields of the t-butylated aromatic hy-

drocarbons. At room temperature and higher, time plays a smaller role and is of real importance only when it is desired to produce t-butylalkylbenzene, which is substantially only the para isomer. When operating at 0° C., the reaction may go for as long as 12 hours; at 120° C. or at other elevated temperatures, the depolyalkylation reaction may be essentially complete in as little as one minute.

When it is desired to produce t-butylalkylbenzene, substantially entirely the para isomer, i.e., on the order of 80 mole percent or more para isomer in the t-butylalkylbenzene product fraction, it is preferred to operate at a temperature between about 20° C. and 50° C. Prolonged times increase the amount of meta isomer present in the product and, therefore, the time is controlled at these temperatures for between about 5 minutes and 30 minutes; in general, the higher the temperature the lower the corresponding time.

The results obtainable with the process are illustrated by several working examples set out below. These working examples involve the use of benzene, toluene, ortho-xylene and meta-xylene as aromatic hydrocarbons and diisobutylene and triisobutylene as the iso-C₄ group donors. The techniques utilized are described in detail in connection with Run 1.

RUN 1

In this run and all the other runs, the aromatic hydrocarbons were nitration grade and the polyisobutylenes were technical grade. The mole ratio of toluene or benzene or xylene to diisobutylene in all the runs was 2. The total hydrocarbon to catalyst volume ratio utilized in the runs was 7.

The runs were carried out utilizing either "fresh catalyst" which had never been used before in any reaction, or "used catalyst," which catalyst had been used at least once in a depolyalkylation reaction. The fresh catalyst was prepared utilizing commercial anhydrous boron trifluoride and distilled water. Typically, a known amount of distilled water was placed in a 4 liter flask equipped with a gas dispersion tube and a Dry Ice cooled condenser. The flask was placed in an ice bath and the BF₃ bubbled into the water until no more was absorbed. The rate of BF₃ addition was controlled to keep the temperature of the liquid in the flask below 35° C. When no more BF₃ was absorbed, the calculated composition, based on BF₃ added was 78.2 weight percent BF₃ and the remainder water. This solution, when analyzed for BF₃ content by conventional procedures, gave a BF₃ weight percent of 76.5. Herein, all BF₃-hydrate type catalyst compositions are given as weight percent of BF₃ found on analysis.

A typical run utilizing toluene as the aromatic hydrocarbon and diisobutylene as the olefin is set out in detail.

Seven moles (644 gms.) of toluene and 190 ml. of BF₃·H₂O were charged to the reactor. Three and one-half moles of diisobutylene (403 gms.) were charged to the dropping funnel. The stirrer was started and water was circulated through the condenser atop the reactor. The diisobutylene was then added dropwise (approx. 25 ml./min.) to the reacting system. The temperature rose from 23 to 36° C. in about two minutes. At this point ice water was circulated through the reactor coils until the temperature dropped to 33° C., then the circulation was stopped. A reaction temperature of 33 to 36° C. was maintained by this method. At the end of 23 minutes all the olefin had been added, after which the stirring was continued for approximately one minute. After the stirrer was stopped, the reaction mixture separated into two layers. The hydrocarbon layer was drawn off into a separatory funnel with a small amount of hydrocarbon being left on the catalyst layer to prevent BF₃ loss to the atmosphere. The hydrocarbon layer was washed with 200 ml. distilled water, then with 200 ml. of 10% KOH and finally washed again with 200 ml. of distilled water. The product was then dried overnight with 150 gms. of calcium chloride.

The product was distilled on a 70-plate hypercal column using a 10:1 reflux ratio. The cuts from hypercal with infrared spectrometer analyses are shown below.

Cut No.	Boiling Range (° F.)	Weight (grams)	Wt. Percent of Total Charged to Dist.	Infra-Red Analysis (Wt. Percent)
10. 1-----	IBP-200	4.8	0.5	82.8% toluene. (28% m-t-butyltoluene. 72% p-t-butyltoluene. 43% 3,5-di-t-butyltoluene.
2-----	200-240	76.7	8.6	
3-----	240-365	4.8	0.5	
4-----	365-400	665.1	74.2	
5-----	400+	135.2	16.2	

The t-butyltoluene produced was blended into a high octane number refinery gasoline base to produce a blend containing 25 volume percent of the t-butyltoluene. The 20 octane number of the blend was determined by the F-1 method (CFR-Research) and the blending octane number of the t-butyltoluene determined. In a base having an F-1 number of 94.6, the t-butyltoluene had a blending octane number of 114. This compares with an octane number, under these circumstances, of 111 for toluene and 109 for a mixture of C₉ aromatic hydrocarbons derived from catalytic reformate. These octane data show that t-butyltoluene is an excellent high octane component of gasoline; an additional very desirable feature is the fact that it is sufficiently high boiling to improve the octane number of the tail end of the gasoline which is frequently deficient in high octane components.

The very high purity para-t-butyltoluene obtainable by the process of the invention is an excellent raw material for the manufacture of para-t-butylbenzoic acid, which material is in considerable demand at this time as a chemical intermediate.

RUNS 2-5

Several runs were made on the preparation of t-butyltoluene from toluene and diisobutylene in order to note the effect of contacting time on the product distribution. In all of these runs, fresh catalyst analyzing 76.5 weight percent of BF₃ was used. All the runs were carried out 45 in the temperature range of 32-37° C. The results of these runs are set out in Table A below.

Table A

Run No.	2	3	4	5
Reaction Time (Minutes)	300	180	32	7
Yields (Mol Percent on Toluene Reacting):				
t-butyltoluene	77.9	82.0	95.9	84.9
3,5-di-t-butyltoluene	7.8	4.7	5.5	3.0
Toluene Reacting	93.0	88.3	88.5	85.0

The data show that when utilizing this particular catalyst at this temperature the depolyalkylation reaction proceeds very rapidly. There is some indication that extremely long contacting time at this temperature has a beneficial effect on the total amount of toluene reacting. However, this extremely long time has the bad effect of increasing the yield of the di-t-butyltoluene at the expense of yield of t-butyltoluene.

The effect of temperature on the reaction product distribution and the reaction itself was studied over a range of temperature. Fresh catalyst was utilized in each run. The results of these runs, studying the effect of temperature, are set out in Table B. All these runs utilize approximately the same reaction times in the range of 150-180 minutes.

The data show that up to a temperature of about 70° C., reaction temperature has very little effect on the total amount of toluene reacting. Also, the amount of di-t-

butyltoluene produced is substantially independent of temperature. However, at about 100° C. the amount of toluene reacting decreased markedly even though the t-butyltoluene yield remained about the same at the expense of di-t-butyltoluene production. With fresh catalyst it appears that the lower temperatures are definitely desirable with respect to maintaining a very high proportion of toluene reacting.

RUN 12

The effect of catalyst age was studied in this run. Most of the tests were carried out at about room temperature for a time of about 300 minutes. Some tests were made under different conditions. Although a total of 15 individual tests were carried out in this run No. 12, only 8 representative tests are set out in Table C following. The reaction conditions, product distribution and particularly isomer distribution used and obtained at various catalyst ages (number of uses) are set out in Table C.

isomer and after run No. 10, in excess of 90% of the t-butyltoluene product fraction is the para isomer.

Other conclusions to be drawn from the data present in Table C are that at constant temperature, as the age of the catalyst increases, time has more bearing on the yield and product distribution. At a given contacting time, as the catalyst ages, higher temperatures are necessary to obtain very high yields.

A second study of catalyst age was made maintaining the reaction temperature at about 33-36° C. and a contacting time of about 28 minutes. The catalyst was reused 27 times for a total of 28 tests. Up through the 24th use, yields in excess of 60% of the toluene charged were obtained, with the t-butyltoluene yields, based on toluene reacting, still in the high 80's. At use 25, and thereafter, the amount of toluene reaction dropped very markedly and on the 28th use there was essentially no reaction. It appears that the catalyst can be reused at least

Table B

Run No.	6	7	8	9	10	11
Reaction Temperature (° C.)	0-5	33-36	45-48	57-60	69-72	100-110
Yields (Mol Percent on Toluene Reacting):						
t-butyltoluene	82.0	86.5	76.7	84.3	85.8	84.5
3,5-di-t-butyltoluene	0.8	5.1	4.9	4.8	6.1	1.2
Toluene Reacting	86.4	87.5	85.6	86.5	86.1	77.4
Product Distribution (Wt. Percent of Total Product):						
IBP-250° F. (Toluene Cut)	8.9	9.4	10.5	10.5	10.2	14.6
250-315° F.	0.4	0.5	0.4	0.4	0.6	0.6
365-400° F. (t-butyltoluene Cut)	74.9	76.1	66.0	72.6	75.1	69.0
400° F. + (3,5-di-t-butyltoluene and diisobutylene polymers)	15.8	14.0	23.1	16.5	14.1	15.8
	100.0	100.0	100.0	100.0	100.0	100.0

Table C

Catalyst Age (Uses)	1	4	7	9	11	12	14	15
Reaction Temperature (° C.)	33-36	18-28	23-30	31-36	5-10	36-38	31-35	34-36
Reaction Time (Minutes)	300	300	330	360	300	270	480	300
Yields (Mol Percent on Toluene Reacting):								
t-Butyltoluene	77.9	82.7	89.8	91.3	81.2	93.8	90.3	89.0
3,5-di-t-butyltoluene	7.8	5.1	1.0	1.2	None	0.5	0.3	None
Toluene Reacting	93.0	99.1	97.0	97.8	85.5	99.0	98.0	82.0
Isomer Distribution (Wt. Percent):								
para-t-Butyltoluene	54	74	85	84	92	92	91	93
meta-t-Butyltoluene	46	26	15	16	8	8	9	7

The data presented in Table C show that at least through 15 successive uses the catalyst is effective in producing very high yields of t-butyltoluene. Examination of the data show that as the catalyst ages the yield of di-t-butyltoluene decreases until at the eleventh use the yield of the di-t-butyltoluene was essentially zero. Of very great interest are the results of the tests with respect to the isomeric distribution of the t-butyltoluene. The tests show that at use 6, not reported, over 80% of the t-butyltoluene product was the para isomer. As the catalyst aged, the distribution shifts markedly to the para

24 times. On this basis, about 10 gallons of alkylate can be produced per pound of BF_3 consumed; this is based on the assumption that the catalyst will not be regenerated, although the catalyst can be recovered at some cost.

RUNS 13-16

In these runs, diisobutylene was reacted with meta-xylene, ortho-xylene and benzene. An attempt was made to react with phenol. The results of these runs are set out in Table D.

Table D

Run Number	13	14	15	16
Aromatic Used	m-Xylene	o-Xylene	Benzene	Phenol
Reaction Temperature (° C.)	33-36	33-36	33-36	45-55
Reaction Time (Minutes)	63	66	58	117
Aromatic/Diisobutylene (Molar)	2.1	2.1	3.1	1.3
Aromatic Reacting	91.9	91.9	56.2	-----
Yields (Mol Percent on Aromatic Reacting):				
1,3-Dimethyl-5-t-butylbenzene	85.6	-----	(1)	(1)
1,2-Dimethyl-4-t-butylbenzene	-----	84.0	(1)	(1)
t-Butylbenzene	-----	-----	78.8	(1)
1,3-di-t-Butylbenzene	-----	-----	.8	(1)
1,4-di-t-Butylbenzene	-----	-----	3.7	(1)
			83.3	

¹ No reaction.

The data show that with benzene as the aromatic hydrocarbon, very little di-t-butylbenzene was produced. About 80% of this was the para isomer. In the case of ortho-xylene, essentially all the product was the 1,2-dimethyl-4-t-butylbenzene showing that under these conditions little or no isomerization takes place.

RUNS 17-18

In these runs, triisobutylene, technical grade, was reacted with toluene. The triisobutylene at a specific gravity of 0.764 at 60° F. boiled over the range of 348° F. to 355° F. Two runs were carried out, one utilizing 70.1 weight percent BF_3 catalyst and the other 76.0 weight percent BF_3 catalyst. The results of these runs are set out in Table E.

Table E

Run Number	17	18
Wt. Percent BF_3 in $\text{BF}_3\text{-H}_2\text{O}$ Catalyst	76.0	70.1
Reaction Temperature (° C.)	24-38	25-33
Reaction Time (Minutes)	54	64
Toluene/Triisobutylene (Mol)	3/1	3/1
Hydrocarbon/Catalyst (Vol.)	7/1	7/1
Yields (Mol Percent on Toluene Reacting):		
t-Butyltoluene	77.7	84.3
3,5-di-t-Butyltoluene	4.1	None
Toluene Reacting	85.2	13.8
Triisobutylene Reacting	99+	25
Isomer Distribution (Wt. Percent):		
m-t-Butyltoluene	38	8
p-t-Butyltoluene	62	92
Toluene Accounted For (Mol Percent)	1.85	98
Triisobutylene Accounted For (Mol Percent)	1.73	87

¹ Remainder of toluene and triisobutylene believed to be in bottoms fraction as heavy polymer and octyl (or higher alkyl) toluene.

The data show that when utilizing about the monohydrate composition, triisobutylene is about as effective in alkylating toluene to the t-butyltoluene as is diisobutylene. Although the lower BF_3 content catalyst was much less effective under these conditions of time and temperature in depolyalkylating the toluene, it is of interest that the t-butyltoluene produced was in excess of 90% of the para isomer.

RUN 19

In this run, it was attempted to depolyalkylate toluene using tripropylene as the olefin. The results of this run show that tripropylene under these conditions does not depolymerize; instead, cracking occurs as well as alkylation with the tripropylene itself. The results of this run are set out in the following table.

Reaction temperature (° C.)	75-80
Reaction time (minutes)	127
Toluene/tripropylene (molar)	1.5/1
Hydrocarbon/catalyst (volume)	7/1
Toluene reacting	70.0

Yields (mol percent on toluene reacting):

Isopropyl toluene	1.0
t-Butyltoluene	5.5
Amyltoluene	14.0
Total depolyalkylate	20.5

Higher boiling aromatics (assumed to be "nonyl" toluene)	51.4

The data set out in the illustrative examples show clearly that by the use of the defined BF_3 -hydrate type catalyst, under the defined conditions of time and temperature, a process results wherein the defined aromatic hydrocarbons can be converted in very high yield to t-butylated aromatic hydrocarbons. Furthermore, the t-butylalkylbenzene products can be made to be substantially entirely the para isomer and can, by a suitable adjustment of time, temperature and catalyst age, be obtained as a fraction containing in excess of 90% of the para isomer.

Thus having described the invention what is claimed is:

1. A process for the preparation of t-butyltoluene containing substantially only the para-isomer, which process comprises depolyalkylating toluene with diisobutylene, in a mole ratio of toluene to iso-C₄ groups in said diisobutylene of between about 1 and 3, in the presence of a BF_3 -hydrate catalyst containing between about 69 and 72 weight percent of BF_3 , the volume ratio of said toluene plus said diisobutylene to said catalyst being from about 1 to 15, at a temperature between about 20° C. and 50° C. for a time between about 5 and 30 minutes, separating catalyst from a hydrocarbon product mixture and recovering from said mixture a t-butyltoluene product fraction containing in excess of 80% of p-t-butyltoluene.

2. The process of claim 1 wherein said mole ratio is about 1.5.

3. The process of claim 1 wherein said volume ratio is between about 5 and 9.
